UNITED STATES PATENT OFFICE

ERNEST THEODORE BAHNER, OF LOS ANGELES, CALIFORNIA, ASSIGNOR TO ROLLODOR MANUFACTURING COMPANY, OF LOS ANGELES, CALIFORNIA, A COPARTNERSHIP COMPOSED OF AMALIA EARLES AND EDGAR H. BARBE

DESIGN FOR AN ASH TRAY

Application filed June 8, 1931. Serial No. 40,109. Term of patent 7 years.

To all whom it may concern:

Be it known that I, ERNEST THEODORE BAHNER, a citizen of the United States, residing at Los Angeles, in the county of Los Angeles, State of California, have invented a new, original, and ornamental Design for Ash Trays, of which the following is a specification, reference being had to the accompanying drawing, forming a part thereof.

In the drawing, the figure is a perspective view showing an ash tray embodying my new design.

I claim:

The ornamental design for an ash tray as shown.

ERNEST THEODORE BAHNER.
